UNITED STATES PATENT OFFICE.

PER ADOLF PETERSON, OF NEW YORK, N. Y.

WELT-GROOVER.

1,152,757.

Specification of Letters Patent.

Patented Sept. 7, 1915.

Application filed February 11, 1911, Serial No. 607,961. Renewed February 4, 1915. Serial No. 6,171.

To all whom it may concern:

Be it known that I, PER A. PETERSON, a citizen of the United States, residing at New York, in the county of New York and State of New York, have invented new and useful Improvements in Welt-Groovers, of which the following is a specification.

The general object of the invention is to facilitate the forming of grooves in welts. 10 And to this end the invention consists of an improved welt grooving tool wherein an extending portion of the head is divided into two projections of unequal length, the shorter of which is sharpened to form a gouge, and the longer forming a guide which contacts with the edge of the welt and invites of the groove being formed in parallel relation with the edge of the welt.

Other objects will appear and be better understood from that embodiment of my invention of which the following is a specification, reference being had to the accompanying drawings forming part thereof, in which:—

25 Figure 1 is a side elevation of the tool. Fig. 2 is a detail perspective view of a portion of the head.

This tool is of simple construction and consists of a handle 5 suitably secured to a head portion 6 formed of the usual tool metal.

Coincident with the end 11 of the head 6

and extending laterally is a relatively wide portion 12 which is divided into two projecting members 9 and 10 by a substantially V-shaped recess 13. The member 9 is sharpened so as to form a gouge. The member 10 being substantially longer than the member 9, contacts with the edge of the welt and forms a guide for the said grooving member 9, and thus admits of the groove being formed in parallel relation with the edge of the welt.

It is evident that one skilled in the art may modify the above described device without departing from the essential features of the same.

What I claim as new and desire to secure by Letters Patent is:

In a welt groover, the combination of a handle, a head connected to the handle and having a laterally extending portion provided with a substantially V shaped recess, whose sides are of unequal length; the longer of the said sides being co-incident with the end of the head and forming a guide, the shorter side having a pointed end forming a groove.

In testimony whereof I affix my signature in presence of two witnesses.

PER ADOLF PETERSON.

Witnesses:

GEO. A. SIMON,
Wm. C. WOLF.
